UNITED STATES PATENT OFFICE.

REUBEN SMITH AND LOUIS J. WERTHEIMER, OF NEW YORK, N. Y.

DESIGN FOR A DISPLAY-FRAME FOR CHILDREN'S CLOTHING.

SPECIFICATION forming part of **Design No. 32,762**, dated **May 29, 1900**.

Application filed April 18, 1900. Serial No. 13,400. Term of patent 7 years.

To all whom it may concern:

Be it known that we, REUBEN SMITH and LOUIS J. WERTHEIMER, citizens of the United States, and residents of the borough of Manhattan, in the city, county, and State of New York, have invented and produced a new, useful, and original Design for a Display-Frame for Children's Clothing, of which the following is a specification, reference being had to the accompanying drawings, forming a part thereof.

In the said drawings, Figure 1 is a front or face view of the frame embodying our design, and Fig. 2 is a plan thereof.

15 *a* is a spirally-shaped loop of one turn or whirl, from which extend, laterally-like, crown branches *b b*, which are slightly curved. The branches *b b* connect, respectively, with arched shoulder-pieces *c c*, from which 20 pend, respectively, side bars *d d*, which curve

inwardly below the shoulders and then flare outwardly at their lower ends and have rounded or loop-like extremities *e e*.

The leading features of our invention are the loop of spiral contour, the branches extending laterally therefrom, and the pendent side bars *d d*.

What we claim is—

The design for a display - frame for children's clothing, substantially as shown and 30 described.

In witness whereof we have hereunto signed our names, this 16th day of April, 1900, in the presence of two subscribing witnesses.

REUBEN SMITH.
LOUIS J. WERTHEIMER.
